UNITED STATES PATENT OFFICE.

ORRELL ASHTON, OF SWAMPSCOTT, MASSACHUSETTS, ASSIGNOR TO UNITED SHOE MACHINERY COMPANY, OF PATERSON, NEW JERSEY, A CORPORATION OF NEW JERSEY.

MACHINE FOR USE IN THE MANUFACTURE OF BOOTS AND SHOES.

1,076,940.

Specification of Letters Patent.

Patented Oct. 28, 1913.

Application filed September 11, 1911. Serial No. 648,635.

To all whom it may concern:

Be it known that I, ORRELL ASHTON, a citizen of the United States, residing at Swampscott, in the county of Essex and State of Massachusetts, have invented certain Improvements in Machines for Use in the Manufacture of Boots and Shoes, of which the following description, in connection with the accompanying drawings, is a specification, like reference characters on the drawings indicating like parts in the several figures.

This invention relates to machines for use in the manufacture of boots and shoes and particularly to shoe shaping machines.

The invention is herein shown as embodied in a machine of the type disclosed in United States Letters Patent No. 1,030,837, granted June 25, 1912. This type of machine comprises a rotary beater which includes a very rapidly rotated carrier or hub having annular end disks, between which disks extend stems or rods arranged around the periphery of the carrier and supporting an annular series of beating elements which strike a very rapid succession of light blows. The beating elements are arranged to be held out radially from the carrier by centrifugal force in normal operative position while the beater is rotating, and to yield inwardly when they strike the work. Machines of this type are employed with great success in pounding up the overlasted marginal portions of shoe upper at the sides of the heel seat and, in some classes of work, along the sides of the shank portion and forepart of the shoe bottom.

An object of the present invention is to provide for a machine of the type above outlined new and improved beating elements, the advantages of which include especial adaptability for leveling the surface being beaten.

Accordingly, a feature of the invention consists in the provision for a machine of the type above mentioned of beating elements which comprise in a preferred form resilient coils somewhat loosely encircling the above mentioned rods. These resilient coils may be supported by the carrier at their ends, but be free to respond to the action of centrifugal force and to yield against that force under pressure of the work at all points intermediate between

their ends. As herein shown for the purpose of illustration, each of these coils consists of a single continuous helical spring, each of these springs being closely wound and, preferably, the alternate springs being oppositely wound so that each spring is reversely wound with relation to each of the springs adjacent to it. The close winding of the springs tends to prevent marring the stock by lining or otherwise marking it. Moreover, the construction above outlined provides that each coil considered as a beating member presents a plurality of convolutions, the joints between which are oblique to the direction of rotation so that the tendency of the convolutions to leave ridges on the surface of the work is further reduced. Also, by oppositely winding alternate coils the said joints are reversely inclined and the convolutions of one coil wipe or beat out any ridges left by the preceding coil. It is to be noted that each convolution of a coil presents a beating element and that these elements are resiliently connected together so that each strikes the work with a force that is augmented by the other elements or convolutions of that coil. This provision renders the coil or beating member more effective for leveling or beating out wrinkles or other inequalities in the surface of the work than separate and disconnected beating elements would be while the beating member or coil as a whole is less harsh than a rigid bar would be. Another advantage possessed by the described construction, when its ends are supported on the rods, over a longitudinal series of separate and disconnected beating elements is that the rattling sound, which accompanies the starting of a beater having loose beating elements which all hang down by gravity when the beater is at rest, is avoided.

These and other features and advantages of the present invention, including certain details of construction and combinations of parts, will be fully set forth and explained in the following detailed description of so much of a machine embodying a preferred form of the invention as is necessary for a complete understanding thereof, and will then be clearly defined in the appended claims.

Referring to the drawings: Figure 1 is an angular perspective in elevation of so much

of the machine as is concerned with the present invention; Fig. 2 is a front view showing in elevation the beater carrier and the beating elements supported thereby; 5 Fig. 3 is a plan view partly in section showing a beating element in operative relation to an edge of the heel seat of a shoe; Fig. 4 is an end view in elevation, showing in detail the operative relation between the beater, the shoe resting and guiding means and the work; Fig. 5 is a front view in elevation showing in detail the relation of the shoe to the beater and the work resting and guiding means in the first position of the 10 shoe; Fig. 6 is a view similar to Fig. 5, showing the last or extreme position of the shoe, with relation to the beater and the shoe resting and guiding means.

Bearings 2 on the frame of the machine 20 support a shaft 4, upon which is mounted a hub or carrier having end disks or flanges 6. The end disks 6 are connected by rods or stems 8 which support an annular series 25 of beating elements 10. The beating elements 10, in accordance with the present invention, comprise resilient coils loosely encircling their respective pivot rods 8. As shown, each of the coils 10 consists of a continuous helical spring restrained at its ends 30 by collars 12, but entirely free at points intermediate between its ends to be moved radially with relation to the axis of the carrier. The beating elements are, as shown in Fig. 1, arranged about the periphery of the carrier and thus constitute, taken collectively, a ribbed cylindrical beating roll normally concentric with the axis of rotation of its carrier, each of the beating elements being, however, mounted eccentrically with 35 relation to the said axis. During the rotation of the roll, the said beating members will be pressed out radially under the action of centrifugal force in normal operative position, the springs at points between 40 their ends bulging outward slightly beyond the periphery of the carrier disks as illustrated in dotted lines in Fig. 2. Under pressure of the work, however, the portions of the springs intermediate between their ends, owing to their said mounting, and also by 45 reason of their resiliency, will yield inwardly and radially against the said force (Fig. 3), each of the springs yielding independently of any of the other springs. 50 At the same time the helical springs are capable of being bent laterally or rearwardly, thus yielding in a circumferential direction independently of their inward yielding.

55 As illustrated clearly in Fig. 2, the coils or springs which constitute the beating members are preferably closely wound. This obviates to a large extent danger of marking or lining the stock, particularly if, 60 as in some uses, the beater is employed for

treating the edge portion of the side of a shoe. Preferably, too, and as best illustrated in Fig. 2, the beating coils are alternately reversely wound so that each coil is oppositely wound with respect to its 70 neighbors. This arrangement produces a very thorough and efficient treatment of the work and, at the same time, tends to aid materially in preventing lining of the stock, the action of one member obliterating marks 75 made by the oppositely directed action of the preceding member.

As shown in Fig. 1, the above described beater may advantageously be employed in conjunction with the plate 14 which extends 80 into close proximity to the outermost position of the beating members, and is adapted to engage the side of the shoe. This plate 14 for resting the shoe coöperates with the beating members in shaping the 85 side of the shoe at and adjacent to the edge of the last by reason of the pressure of the shoe against it. The said plate may be stationary or conveniently, to facilitate its co-operative action, it may be actuated by suitable means to beat or rub the upper.

For beating the sides and the bottom of the heel portion of the shoe and also the sides of the forepart of the shoe bottom, the shoe may be rested on a horizontal member 95 16, as illustrated in Figs. 5 and 6. In the common use of the machine for heel seat beating, the said member 16 will thus serve as a rest for one side of the heel portion of the shoe at a time for presenting the shoe 100 to the beater for treatment of the heel seat at the other side, as clearly shown in Fig. 4. Preferably, and as shown, the upper face of the member 16 is convexly rounded to facilitate turning the shoe from the first position shown in Fig. 5 to the extreme position shown in Fig. 6, and to insure that during this turning the successive portions presented to the beater will be in the same horizontal plane, thus compensating for the 110 lift of the shoe.

As shown in Fig. 1, the member 16 may have associated with it a vertical guide or rest which consists of a relatively thin plate 18, having a horizontal extension 20 supported upon a flat part 22, fixed to an upright post 24 which is adjustably secured in a bracket on the machine frame by a set screw. The horizontal rest 16 caps the extension 20 of the vertical guide 18 and a set 115 120 screw 23 passing through a hole in the part 22 and through a somewhat elongated transverse slot in the extension 20, has screw threaded engagement with the rest 16, thereby binding the said parts together. By 125 reason of the elongated transverse slot in the extension 20, the vertical guide 18 can, if desired, be adjusted toward or from the beater.

The end portions of the guide 18 form at each lateral side of the rest 16 vertical stops 130

26 which are intended and arranged, as shown in Figs. 5 and 6, to engage the heel side of the rear partially driven side lasting tack 25 on the side of the shoe supported by the rest 16. These stops during the action of the beater upon the heel seat at the other side, serve to restrict lengthwise movement of the shoe heelward, limiting the field of action of the beater so as to prevent engagement of the beater with the portion of overlasted upper held by the side lasting tacks. The member 18 also constitutes a guard to prevent the beater from engaging and forcing toward the edge of the 10 last bottom the upper on the lower side of the heel seat while the beater is forcing inwardly the upper on the upper side of the heel seat. If it is desired to extend the field of operation to the shank region of the shoe, the vertical member instead of engaging a 15 rear side lasting tack may be interposed between the beater and the side lasting tacks on the lower side of the shank, and by such interposition prevent these tacks from being disturbed during treatment of the shank at the upper side. Preferably, the upper corner portions of the vertical rest 18 are rounded similarly (Fig. 1) to the upper face of the member 16. As a result, for manipulating the shoe from the first position shown 20 in Fig. 5 to the last or extreme position shown in Fig. 6, the shoe may be rocked about the rest 16 without disturbing the guiding engagement of the member 18 with the rear side lasting tack 25 which will slide along the edge of the member 18 as the shoe is turned.

In order to facilitate tipping the shoe transversely of its longitudinal axis, causing the side of the heel seat to be treated to bear against the beater with the required pressure and at the desired angle, the upper and end edge portions of the vertical member 18 may be beveled as illustrated in 45 Fig. 1.

The novel features of the above-described work resting and guiding means together with the combination of said means with the beater are not herein claimed since they constitute the subject matter of a co-pending divisional application, maturing in United States Letters Patent No. 1,032,356, dated July 9, 1912.

Having thus fully described one illustrative embodiment of this invention, what I claim as new and desire to secure by Letters Patent of the United States is:

1. In a machine of the class described, a rotary beater comprising a carrier and a plurality of beating members consisting of spiral coils arranged about the periphery of the carrier and mounted to permit them to move radially with relation to the axis of the carrier.

2. In a machine of the class described, a

rotary beater comprising a carrier and a plurality of beating members supported thereon, each of the said members consisting of a spiral coil connected at its ends to said carrier and the convolutions of which coil constitute resiliently connected beating elements. 70

3. In a machine of the class described, a beater comprising a carrier and a plurality of beating members arranged about the periphery of the carrier, each of said members extending transversely of said periphery and consisting of a series of resiliently supported beating elements. 75

4. In a machine of the class described, a beater comprising a rotary carrier and a plurality of beating members connected at their ends to said carrier and arranged to be free to move between their ends radially with relation to the axis of the carrier, each of said beating members consisting of a spiral coil the convolutions of which constitute resiliently connected beating elements. 80

5. In a machine of the class described, a rotary beater comprising a carrier having arranged about its periphery a plurality of beating members each comprising a series of resilient beating elements extending lengthwise of the carrier, the adjacent faces of the beating elements being inclined to 95 the direction of rotation of the carrier.

6. In a machine of the class described, a rotary beater comprising a carrier having arranged about its periphery a plurality of beating members each comprising a series of beating elements extending lengthwise of the carrier, the adjacent faces of the beating elements being inclined to the direction of rotation of the carrier, and the lines between adjacent beating elements in successive members being oppositely inclined. 100

7. In a machine of the class described, a rotary beater comprising a carrier and an annular series of beating members consisting of resilient coils arranged about the periphery of the carrier, the alternate coils of said series being oppositely wound, for the purpose described. 110

8. In a machine of the class described, a rotary beater comprising a carrier and a plurality of beating members consisting of spiral coils arranged about the periphery of the carrier, the said coils being supported at their ends by the said carrier and unsupported between their ends and arranged to be held outwardly by centrifugal force in normal operative position during the rotation of the carrier, and to yield inwardly against that force under pressure of the work. 115

9. In a machine of the class described, a rotary shaft, a pair of disks carried by the shaft, beating member supports on said disks, and beating members mounted on said supports between the disks, the said beating 120

125

130

members comprising resilient coils encircling the supports and at their ends maintained in axial relation to the supports while being arranged to yield between their ends 5 toward and from the axes of their respective supports.

10. A rotary beater comprising a carrier and a plurality of beating members arranged about the periphery of the carrier 10 and consisting of closely wound resilient coils supported at their ends by said carrier and free to yield independently and inwardly at points between their ends under pressure of the work.

15. 11. A rotary beater comprising a carrier and a plurality of beating members mounted eccentrically with relation to the axis of rotation of the carrier, the said members consisting of resilient coils arranged to be 20 free to move radially at points intermediate between their ends.

12. A rotary beater comprising a carrier and a plurality of beating members consisting of an annular series of resilient coils arranged about the periphery of the carrier and extending lengthwise thereof to form collectively a normally cylindrical beating surface concentric with the axis of rotation of the carrier.

30. 13. A rotary beater comprising a carrier and a plurality of beating members consisting of an annular series of resilient coils arranged about the periphery of the carrier, and mounted to permit them to be held outwardly by centrifugal force in normal operative position during the rotation of the carrier, and to yield inwardly against said force under pressure of the work, whereby said beating members successively engage 40 the work with a beating or hammering action and a subsequent rubbing or smoothing action.

14. In a machine of the class described, a rotary beater comprising a carrier and an 45 annular series of beating members mounted on the carrier, the said beating members consisting of resilient coils connected at their ends to said carrier and arranged during the rotation of the carrier to bulge outwardly beyond the periphery of the carrier 50 at points between their ends under the action of centrifugal force.

15. A shoe shaping machine comprising a rotary carrier, a plurality of beating member supports arranged about the periphery of the carrier and extending lengthwise continuously thereacross, and a series of beating members on the said supports, the said beating members comprising resilient coils 60 encircling the supports and having their ends confined against radial movement.

16. In a machine of the class described, a rotary shaft, a pair of disks carried by the shaft, beating member supports on said 65 disks, beating members mounted on said

supports between the disks, and collars on the supports confining the ends of the beating members, the said beating members comprising resilient coils arranged to be movable radially between their ends, and having 70 their radial movement limited by the extensions of the supports beyond the collars.

17. In a machine of the class described, a rotary shaft, a pair of disks carried by the 75 shaft, beating member supports on said disks, and beating members mounted on said supports between the disks, the said beating members comprising resilient coils encircling their supports and arranged to be moved outwardly between their ends under the influence of centrifugal force during the rotation of the shaft to an extent limited by the said beating member supports.

18. A rotary beating-up or like device comprising beating or operating members 80 consisting of helical springs supported and held at their ends and having yielding central portions, said springs being arranged in an annular series around the axis of rotation and disposed in close proximity one 85 to another so that the sides of said springs form the outer circumferential operating surface of the device.

19. A rotary beating-up or like device comprising an annular series of helical 90 springs supported and held at their ends and having central portions capable of yielding, said springs being formed of flat section material closely wound so as to form an approximately flat and unbroken operative 95 surface in a longitudinal direction.

20. A rotary beating-up or like device comprising an annular series of helical springs supported and held at their ends and having central portions capable of yielding, 100 said annular series being composed of springs which are relatively different one from another as regards the direction of their helices, substantially as and for the purpose described.

21. In a machine of the class described, a rotary beater comprising a carrier, a plurality of individually yielding beating members arranged in a circumferential series thereon, and means determining the normal 115 outward position of said members and permitting them to yield outwardly from such position in a substantially radial direction relative to said rotary carrier under the action of centrifugal force.

22. In a machine of the class described, a rotary beater comprising a carrier, a plurality of resilient beating members arranged about the periphery of the carrier to extend transversely of said periphery and unyieldingly confined at their ends against outward displacement by centrifugal force while free to spring outwardly between their ends under the action of said force.

23. In a machine of the class described, a 130

rotary beater comprising a carrier, a plurality of beating members arranged about the periphery of the carrier to extend transversely of said periphery, each of said members comprising a series of resilient beating elements having a normal position with respect to the periphery of the beater but capable of displacement along radial lines under the influence of centrifugal force,

and means for determining the normal position of the beating elements.

In testimony whereof I have signed my name to this specification in the presence of two subscribing witnesses.
